(57) **CLAIM**

The ornamental design for a garment, as shown and described.

DESCRIPTION

FIG. 1 is a rear perspective view of an athletic short showing the new design for a pocket;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a rear perspective view of an alternate embodiment of an athletic short showing the new design for a pocket, the only difference being the omission of the left pocket;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof;

FIG. 14 is a bottom plan view thereof;

FIG. 15 is a rear perspective view of an alternate embodiment of an athletic short showing the new design for a pocket, the only difference being the omission of the right pocket;

FIG. 16 is a front elevation view thereof;

FIG. 17 is a rear elevation view thereof;

FIG. 18 is a left elevation view thereof;

FIG. 19 is a right elevation view thereof;

FIG. 20 is a top plan view thereof; and,

FIG. 21 is a bottom plan view thereof.

The broken lines shown comprise environment for illustrative purposes only and form no part of the claimed invention.

The cross-hatch pattern applied to the drawings represents fabric.

1 Claim, 12 Drawing Sheets
